UNITED STATES PATENT OFFICE.

CLARENCE S. LUITWIELER, OF BOSTON, MASSACHUSETTS.

CARTON-MARKING MACHINE.

SPECIFICATION forming part of Letters Patent No. 766,634, dated August 2, 1904.

Application filed November 22, 1902. Serial No. 132,397. (No model.)

To all whom it may concern:

Be it known that I, CLARENCE S. LUITWIELER, a citizen of the United States, residing at Boston, in the county of Suffolk, State 5 of Massachusetts, have invented a certain new and useful Improvement in Carton-Marking Machines, of which the following is a specification, reference being had therein to the accompanying drawings.

10 My invention consists in a power-actuated marking or printing machine having a start and stop driving mechanism and means whereby when a carton or box is applied to the printing-bed or work-support the said mechanism is rendered operative to actuate the marking or printing devices to mark or print upon the flap or end of the said carton or box, all being arranged and operating to render the marking or printing devices normally inoperative to mark or print and to bring the said devices automatically into action when a carton or box is applied as aforesaid, in order to effect the marking or printing of the the said carton or box.

25 While in making the invention I have had in view more particularly the marking of cartons or boxes, the invention is not necessarily restricted to use for this precise purpose.

In the accompanying drawings, Figure 1 30 illustrates a machine containing an embodiment of the invention, the bed of the machine being in vertical section and certain of the parts at and adjacent the clutch being broken away in order to show the features of construction more clearly. Fig. 2 shows in plan the printing-bed and certain parts adjacent the same.

Having reference to the drawings, the bed of the machine is designated 1.

40 2 designates the printing-head, 21 being the carrying-arm for the said printing-head and the said carrying-arm being provided with trunnions 22, which are fitted to bearings which are provided in lugs 23, rising from the bed 1.

45 Usually in practice the said arm 21 is in operative engagement with an actuating-cam (not shown) upon the cam-shaft 3 of the machine, the said cam-shaft being journaled in bearings which are provided in lugs 31 on the bed 1. By the action of the said cam the arm 21

is operated to depress the printing-head from its position shown in the drawings, so as to cause the printing devices to make contact with the work resting upon the printing-bed, and then is raised again.

55 At 24 is indicated a portion of the printing devices proper which are carried by the head 2, the said devices usually comprising a series of wheels mounted side by side in the head 2, having suitable printing characters around their respective peripheries and rotarily adjustable in well-known manner to enable any required combination of characters to be brought into the printing position on the said head.

60 At 4 is the printing-bed or work-support, it being usually provided in practice with a cushion 41, of rubber or other suitable material, upon which the work rests, the said printing-bed or work-support being located at the 65 outer end of a stand or bracket 42, which is mounted upon the bed 1 and projects forwardly therefrom.

65 At 5 is the inking-pad and at 51 the inking-pad carrier, 52 being a link by means of which the said carrier 51 is suspended from the outer portion of the arm 21, carrying the printing-head, the said carrier 51 having a rearwardly-extending arm 53, which is connected at 54 pivotally with an arm 55, the latter being 70 pivoted at its lower end, as at 57, upon bed 1 and having a roll or the like at 56, that is engaged by a cam 58 upon the cam-shaft 3. Through the action of the said cam the required movements of the inking devices are occasioned.

75 As thus far described the parts of the machine are substantially the same as in prior marking-machines and description of the construction of the machine in detail is unnecessary. One use that I contemplate making of the invention is in the marking of cartons or boxes for containing shoes. When this is the case, the printing-wheels, which are mounted in the head 2, will bear printing characters 80 suitable for marking upon the end or flap of a carton or box the size, width, lot number, material, and style, or such other features and characteristics as it may be desired to indicate upon the exterior of the carton.

The power-driving appliances in connection with the machine comprise a band-pulley 6, to which in practice driving power is transmitted by means of a driving-band. (Not shown.)

5 The said band-pulley 6 is fast upon a driving-shaft 61, which is mounted in bearings that are provided in lugs 62, rising from the bed 1, and the said driving-shaft has fast thereon a toothed pinion 63, meshing with a toothed gear 64, that is mounted upon the cam-shaft 3. The said gear 64 is loose upon the cam-shaft 3. In the present instance the clutching devices by means of which at the required times the gear 64 is connected or clutched 10 with the cam-shaft 3 comprise a toothed wheel, as 65, fast with the gear 64, an arm, as 66, mounted upon the cam-shaft 3 and made fast thereon, as by means of a clamping-screw 67, and a dog 68, which is pivoted upon the said 15 arm 66, as at 69, one end of the said dog being shaped suitably to enter the respective spaces between the teeth of the toothed wheel 65. When said end of the dog is permitted to enter one of the said spaces, the cam-shaft 20 3 and toothed wheel 65 are locked together, with the result that driving power is transmitted to the cam-shaft and the printing mechanism is operated. A tension-spring 7, having one extremity thereof connected to the 25 dog 68 and the other extremity thereof connected to a pin 71 on the arm 66, tends to draw the dog 68 into engagement with the toothed wheel 65. For the purpose of disengaging the dog 68 from the toothed wheel 65 the clutch-30 controller 8 is provided. This is in the form of a lever and is pivoted at 81 to a lug 82, depending from the top of the bed 1. The rear extremity of the clutch-controller 8 extends into proximity to the cam-shaft 3 and in the 35 normal position of the clutch-controller lies within the path which is described by the tail of the dog 68 when the dog is engaged with the toothed wheel 65 and the said dog, the arm 66, and cam-shaft 3 are rotating in unison with the said wheel. The encounter of the 40 tail of the dog with the face 83 of the clutch-controller during the rotation of the parts aforesaid results in the disengagement of the dog from the toothed wheel 65, which un- 45 clutches the toothed wheel from the cam-shaft. The clutch-controller 8 has a projection or toe 84 constituting a stop which contacts with a like projection or toe 85 on the outer end of the arm 66. The disengagement 50 of the dog 68 from the toothed wheel 65 is succeeded immediately by encounter of the toe 85 on the arm 66 with the toe 84 of the clutch-controller 8, whereby the forward movement of the cam-shaft is arrested pos- 55 tively, the said cam-shaft and parts carried and operated thereby being brought to a state of rest. To prevent rebound of the cam-shaft when arrested in the manner just described, the clutch-controller 8 is furnished 60 with a shoulder at 86, against which the end 65

of the tail of the dog takes so as to prevent backward movement of the arm 66 and cam-shaft.

For the purpose of enabling the clutch-controller to be operated by a carton or box when the latter is applied in position to be marked or imprinted a movable gage, as 9, is mounted upon the stand or bracket 42 at the rear of the printing-bed or work-support 4. This gage 9 has a base 91, fitted upon the top of a 70 slide 92, working in a slot 93, which is formed in the stand or bracket 42. The slide 92 is pressed forward toward the printing-bed or work-support 4 by means of a spring 10. The gage 9 is adjustably secured upon the slide 92 75 by means of a screw 11, the base of the gage 9 being formed with a longitudinal slot 110, through which the stem of the said screw passes, the said slot permitting adjustment of the gage in a direction toward and from the 80 printing-bed 4. This adjustment of the gage 9 provides for the marking or printing of cartons or boxes having flaps or ends of various widths. The gage 9 is held normally by the action of the spring 10 in a position to receive the pressure of the rear edge of the flap or end of a carton or box when the said flap or end is placed upon the printing-bed or work-support 4. As the carton or box is pressed rearwardly relative to the said printing-bed or work-support 85 to place the required portion of its flap or end in position to receive the marking or imprint the edge of the flap or end presses back or rearward the gage 9, and the movement of the said gage is suitably transmitted to the clutch-controller 8 to operate the latter. In the present instance the slide 92 is formed with a depending portion, in which below the main portion of the stand or bracket 42 is formed an oblique or inclined slot 921, receiving a pin 90 or the like, as 922, with which the forward extremity of the clutch-controller 8 is provided. In the normal position of the parts before the carton or box is applied to the printing-bed or work-support the gage 9 occupies 95 its forward position, (shown in Fig. 1,) being held there by the spring 10, and the rear portion of the inclined slot 921 holds the forward extremity of the clutch-controller 8 depressed and its rear extremity in engagement with the 100 arm 66 and dog 68. Rearward movement of the slide 92, occasioned, for instance, by the pressure of the edge of the flap or end of a carton or box against the gage 9, causes the clutch-controller to be moved, so as to depress 105 its rear extremity, thereby freeing the arm 66 and dog 68, whereupon the spring 7 draws the dog into engagement with the toothed wheel 65, thus clutching the cam-shaft 3 and toothed wheel 65 together. The cam-shaft 110 makes one revolution, during which the printing-head is caused to descend upon the flap or end of the carton or box resting upon the printing-bed or work-support and again rise, and the carton or box being removed as soon 115

as the printing-head rises sufficiently, so as to release the gage 9 and permit the slide and gage to be moved forward into their normal position by the spring 10, the clutch-controller

5 8 is permitted to resume its normal position and unclutch the driving power, it also locking the cam-shaft from further movement for the time being.

What I claim is—

10 1. In combination, the printing-head, the inking device coöperating with said printing-head, a start and stop driving mechanism in operative connection with the said printing-head and inking device to actuate the same,

15 a printing-bed or work-support, and controlling and stopping means operated by an article applied to the said printing-bed or work-support to be printed to actuate the said means.

2. In combination, the printing-head, the

20 inking device coöperating with said printing-head, a start and stop driving mechanism in operative connection with the said printing-head and inking device to actuate the same and comprising essentially a wheel, a dog to

25 engage said wheel, a carrier for said dog, and a dog-controller and stop device, a printing-bed or work-support, and means operated by an article applied to the said printing-bed or work-support to be printed to actuate the said

30 dog-controller and stop.

3. In combination, a printing-head, a start and stop driving mechanism therefor comprising essentially a clutch-wheel, a clutch-dog to coöperate with said clutch-wheel, a carrier for

35 said clutch-dog, controlling and stopping means to control the engagement of the clutch-dog with the clutch-wheel, and hold the parts from further movement and also from re-

bound, a printing-bed or work-support, and means operated by an article applied to the 40 printing-bed or work-support to be printed to actuate the said controlling and stopping means.

4. In combination, a start and stop driving mechanism provided with a clutch device comprising, essentially, a toothed wheel, a pivoted dog to engage with said wheel, a carrier for said pivoted dog, a printing-head operated by said mechanism, a printing-bed or work-support, a controller and stop to coöperate with 45 the said dog to open the clutch and also to engage with the said carrier to arrest the movement of said printing-head and with the said dog to prevent rebound, and means operated by an article applied to the said printing-bed or work-support to be printed to actuate the said controller and stop.

5. In combination, a start and stop driving mechanism provided with a clutch device comprising, essentially, a toothed wheel, a pivoted 50 dog to engage with said wheel, a carrier for said pivoted dog, a printing-head operated by said mechanism, a printing-bed or work-support, a controller and stop to coöperate with the said dog and carrier, and a slide adjacent 55 the printing-bed or work-support having a cam-slot to operate the said controller and a gage whereby the said slide is operated by an article applied to the said printing-bed or work-support to be printed.

In testimony whereof I affix my signature in presence of two witnesses.

CLARENCE S. LUITWIELER.
